Patented Mar. 23, 1920.

UNITED STATES PATENT OFFICE.

WALTER H. HUTH, OF CHICAGO, ILLINOIS.

TOY FIGHTING-TANK.

1,334,539.

Specification of Letters Patent. Patented Mar. 23, 1920.

Application filed March 21, 1918, Serial No. 223,790. Renewed September 18, 1919. Serial No. 324,581.

To all whom it may concern:

Be it known that I, WALTER H. HUTH, a citizen of the United States of America, and resident of Chicago, county of Cook, and 5 State of Illinois, have invented a certain new and useful Improvement in Toy Fighting-Tanks, of which the following is a specification.

This invention relates to mechanical toys 10 of the kind that are made to resemble the so-called tanks now in use by the British Army in France, and which comprise a body within which the power-plant and other essentials are inclosed, and which are propelled by caterpillar traction devices.

The object of the invention is to provide a novel and comparatively cheap construction which will result in a toy that resembles the so-called fighting tank in appearance, 20 and which will travel on the floor and over obstacles, and which will constitute an attractive mechanical toy.

To these and other useful ends, the invention consists in matters hereinafter set forth 25 and claimed, and shown in the accompanying drawings, in which:—

Figure 1 is a perspective of a toy fighting tank embodying the principles of the invention.

30 Fig. 2 is a longitudinal section of the toy shown in Fig. 1 on line 2—2 in Fig. 3.

Fig. 3 is a plan of said toy.

Fig. 4 is a transverse section on line 4—4 in Fig. 2.

35 Fig. 5 is a fragmentary detail view illustrating a portion of the construction.

Fig. 6 is a detail section on line 6—6 in Fig. 3.

As thus illustrated, the invention comprises 40 a sheet metal body composed of flat sides 1 which are spaced apart and tapered at their ends, the forward end tapering upwardly and the rear end tapering downwardly thereby to give the toy the desired 45 outline in side elevation. The two walls 1 are rigidly held together by a sheet metal top wall 2 which extends forward and downward to the point 3 on the inclined underside of the front portion of the toy, and

50 which extends downward and around to the point 4 on the bottom of the rear portion thereof, so that the greater portion of the bottom is left open. The wall 2 has its edges provided with lugs 5 inserted through openings 6 in the side walls 1, and suitably bent 55 to fasten the sides and top rigidly together.

The sides are also connected together by transverse cylindric members 7, 8, 9 and 10, disposed adjacent the four corners of the sides, and upon these cylindric members 60 rollers 11 are mounted. These rollers have grooved peripheries, the bottom of each groove being preferably convex, (see Fig. 4) and the endless belts 12 extend tightly around these rollers, said belts having roughened tread portions to travel on the floor or on the ground. Preferably, each belt is made of rubber, or of rubber and fabric, so that each belt can be stretched sufficiently to enable it to hold itself tightly in contact 70 with the rollers. With this arrangement, the rollers 11 on the rear member 7 are rotated, in a suitable manner, by a gearing 13 connected to a spring motor, (not shown) of any suitable character, with the result that 75 the bottom portions of the two endless traction belts travel backward, while the upper portions thereof travel forward. In this way, caterpillar traction devices are employed for propelling the toy, in a manner 80 that will be readily understood. It will be seen, of course, that the top wall 2 must be notched at 14, 15 and 16 to receive some of the rollers 11, and that the belts 12 slide forward upon the upper surface of the top wall 85 2, when the toy is in operation.

From the foregoing it will be seen that a toy fighting tank is provided which can be very economically manufactured, but which will be attractive in appearance, and which 90 will have the requisites of the original fighting tanks previously mentioned. The toy can be of any suitable size, but is preferably large enough to climb over obstacles, and to cross from one side of a space to the other, 95 and to in this way simulate the actions of the full-sized fighting tank. The rubber belts 12 furnish proper traction, and as they are stretched before they are put over the rollers 11, it follows that these belts will 100 stay in place, and will have sufficient frictional contact with the rollers 7 to be driven in the desired manner.

The bottom portions of the belt 12 preferably bear upward against small rollers 17 105 which are journaled on the inner sides of the side walls of the toy, and which have flat treads to bear upon the belts. In this way, as previously explained, the bottom of the toy is practically open, but the belts 12 are 110 in position to support the weight and to propel the toy forward on the floor.

The traction belts 12 have their treads roughened in any suitable manner, and formed of rubber or other elastic or resilient material, and preferably this is done by 5 transversely grooving or corrugating the tread surface of each belt. With this arrangement, each caterpillar traction belt is flexible and resilient in character, and is preferably sufficiently elastic to permit it to 10 be stretched over the rollers, so that the tension resulting from this stretching will hold the belts tightly on the rollers, particularly the rollers which drive the belts.

The toy is so shaped, it will be seen, that 15 it will climb obstacles, such as books or other things laid on the floor, and for this purpose the front end is preferably inclined forward, and the belts extend around the rollers 11 which are located at the front end. 20 Also, as shown, the rear end is inclined forward, and the rollers 11, it will be seen, are all located in the corners between the top and bottom and ends of the body, so that these rollers are placed wherever the flexible 25 belt changes its angle or direction of travel on the outer surface of the body.

What I claim as my invention is:—

1. A toy fighting tank comprising caterpillar traction devices formed by one or 30 more elastic bands with the elastic material thereof in direct contact with the surface over which the toy travels, thereby increasing the traction and presenting a cushion tread to the surface over which it travels. 35 2. A toy comprising caterpillar traction devices formed by one or more bands having rubber therein to form cushion treads and to insure elasticity to keep the bands tight, and with the rubber treads roughened 40 to increase the traction.

3. A toy fighting tank comprising caterpillar traction devices formed by one or more flexible bands of fabric and rubber, with the rubber itself forming cushion 45 treads in direct contact with the surface over which the tank travels, and the rubber treads of said band or bands being roughened to increase the traction.

4. A toy fighting tank comprising side 50 walls spaced apart, inclosing means rigidly connecting said walls together to form a hollow body, upper and lower rollers between said walls, endless caterpillar traction belts on said rollers, said belts traveling on the outer surface of said inclosing means, so that each entire belt is exposed, and two 55 rows of smaller rollers to support the weight on the lower portions of said belts, said inclosing means forming a top wall which is

notched at opposite sides to afford spaces 60 for some of said rollers, and transverse members having their ends extended through the side walls to support the larger rollers.

5. A toy fighting tank comprising a hollow body having flat side walls, a flat bottom, a front end which is inclined forward, a rear end which is also inclined forward, a substantially flat top countersunk and interposed between the upper edges of the side walls, rollers disposed at the four corners between the top and bottom and ends, and endless caterpillar traction belts extending around said rollers and over the top of the body, and underneath the body inside of said upper edge, each belt being conformed 75 to the outline of the body.

6. A structure as specified in claim 5, in combination with two rows of smaller rollers to engage the bottom portions of the belts to support the weight of the toy thereon, and means to rotate the rollers at the rear end of the toy to operate said belts to 80 drive the toy forward.

7. A toy fighting tank comprising a hollow body having a top and a bottom and 85 front and rear ends, the front end being inclined forward, flat sides, rollers inclosed in said body, said body having openings through which the rollers extend, shafts extending through the sides to support said 90 rollers, and endless caterpillar traction belts extending entirely around the body, each belt being engaged by some of said rollers, and devices to operate one or more of said rollers to operate the traction belts and 95 thereby propel the toy forward.

8. A toy fighting tank comprising caterpillar traction devices formed by elastic bands.

9. A toy fighting tank comprising caterpillar traction devices formed by bands having rubber therein to insure elasticity to 100 keep the bands tight.

10. A toy fighting tank comprising caterpillar traction devices formed by flexible 105 and resilient bands.

11. In a traveling toy having caterpillar traction, the combination of a flexible band having a smooth inner surface and an outer tread surface, and rollers to support and 110 drive said band, the material of the band being elastic to keep it stretched tightly around said rollers, so that one roller has sufficient frictional engagement to drive the belt.

Signed by me at Chicago, Cook county, Illinois, this twelfth day of March, 1918.

WALTER H. HUTH.
